US00D909985S

(12) **United States Design Patent** (10) Patent No.: **US D909,985 S**
(45) Date of Patent: **** Feb. 9, 2021**

(54) **ELECTRONIC DEVICE**

(71) Applicant: **Spotify AB**, Stockholm (SE)
(72) Inventors: **Richard Landerus**, Stockholm (SE);
Jonas Samrelius, Stockholm (SE)
(73) Assignee: **Spotify AB**, Stockholm (SE)
(**) Term: **15 Years**
(21) Appl. No.: **29/646,733**
(22) Filed: **May 7, 2018**
(30) **Foreign Application Priority Data**

Jan. 3, 2018 (EM) 004734127-0001

(57) **CLAIM**

The ornamental design for an electronic device, as shown and described.

DESCRIPTION

FIG. 1 is front isometric view of an electronic device according to the present disclosure;
FIG. 2 is a rear isometric view thereof;
FIG. 3 is a left side view thereof;
FIG. 4 is a rear view thereof;
FIG. 5 is a front view thereof;
FIG. 6 is a right side view thereof; and,
FIG. 7 is a bottom view thereof.
